DESIGN FOR A DOLL HEAD

William Seidler and Otto Feuer, New York, N. Y.

Application December 13, 1945, Serial No. 124,697

Term of patent 3½ years

(CL. D34—4)

To all whom it may concern:

Be it known that we, William Seidler and Otto Feuer, both citizens of the United States and residents of New York city, in the counties of New York and The Bronx, respectively, and State of New York, have invented a new, original, and ornamental Design for a Doll Head, of which the following is a specification, reference being had to the accompanying drawing, forming a part thereof, and of which Fig. 1 is a view in front elevation of a doll head showing our new design; Fig. 2 is a side view thereof; and Fig. 3 is a rear view thereof.

We claim:

The ornamental design for a doll head, substantially as shown.

WILLIAM SEIDLER.
OTTO FEUER.
